UNITED STATES PATENT OFFICE

EDWARD ELLSBERG, OF WESTFIELD, NEW JERSEY

UNDERWATER TORCH AND METHOD THEREFOR

Application filed December 20, 1927. Serial No. 241,387.

My present invention relates more particularly to blow torches for cutting and for autogenous welding of metal. It involves discoveries whereby it is made commercially

5 practical to cut metal under water and particularly to perform such operation in a reliable manner on a commercial basis at great depths.

As is well known, metal cutting torches 10 utilize a mixture of fuel gas and pure oxygen discharged in a composite jet flame adapted to locally heat the metal to a high temperature, whereupon a jet of pure oxygen is blown through the flame onto the hot 15 spot to melt or burn away the metal, the operation being carried on progressively along the line of the desired cut. In the present state of the art, acetylene and other 20 of the higher hydrocarbon gases or mixtures thereof with hydrogen, are used as the fuel constituent of the jet, because of their great fuel value per unit volume.

It has long been proposed and often attempted to perform similar metal cutting 25 operations under water, as in submarine construction and ship salvage work, by surrounding the blow pipe flame with a sheath of air for the purpose of isolating the flame and excluding the water from the 30 surface of the metal on which the flame is directed. In connection with my work in the United States Navy, I have investigated and tested all of the most promising of the suggested ways of doing this, with the result 35 that all of them have proved unreliable and frequently dangerous under relatively small depth pressures, say, 15 to 30 feet and all of them have proved entirely inoperative for the greater depths at which divers frequently 40 do their ship salvage work. My invention involves discovery and solution of all of the difficulties which have heretofore beset such under-water metal cutting operations.

45 In torches of this kind, submarine or otherwise, the ratio of fuel gas to oxygen and its proper mixture must be carefully regulated in order to effect the required pre-heating of the metal and the cutting there- 50 of by the supplemental oxygen jet.

Heretofore it has been found extremely difficult and in practice impossible, to satisfactorily effect such adjustments under water for various reasons. It is difficult enough even in above-water work. The low 55 visibility under water makes it difficult to see the apparatus and the work, and it is still more difficult to judge the flame conditions within the bubbling air envelope. Furthermore, the combustion conditions of 60 the jet are very different from those in the atmosphere; where the pressure is practically constant, it is 15 pounds per square inch. Under water, however, even one foot increase or decrease of depth causes a change 65 of approximately $\frac{1}{2}$ pound in the pressure the water exerts upon the flame supply jets. Thus, at a depth of only 30 feet, the pressure is increased to 15 pounds per square inch above atmosphere, while at a workable depth 70 of 180 feet, it is 90 pounds per square inch above atmosphere. These multiplied pressures correspondingly multiply the density of the gases in the flame within the bubble and also the back pressure on the jets which 75 supply the bubble. Consequently, the speeds of the gases emerging from the torch are proportionally reduced while the speed of propagation of the flame is proportionally increased. For both of these reasons, 80 the liability of the torch to back fire increases rapidly with increase of depth. As a result it has been found impractical for a diver to properly adjust his mixture under practical conditions of under-water work. 85 Consequently, gas pressures for the torch have generally been controlled from above-water in accordance with carefully prepared charts or tables of depth pressures, for the fuel gas, for the oxygen, and for the air 90 sheath, the basic pressure for proper operation at the shallowest depth, being determined by a very careful test under laboratory conditions. While this is the best that can be done in accordance with the prior 95 art, it proves entirely unsatisfactory under the conditions of practical use by a diver where it is seldom possible to determine the precise depth of the torch, either initially, or as the work progresses. Moreover, such 100

predetermined methods do not work out to accommodate varying qualities, temperatures or conditions of the fuel gas or variations in manipulation of the torch by the diver.

To meet these conditions, one feature of my invention involves working out and demonstration that it is practical to establish what amounts to laboratory conditions for the diver to pre-adjust his jet for maximum heating effect on the metal; regardless of the depth at which he is working, and immediately to apply the thus adjusted jet to the work under the same conditions and with the same maximum heating effect. For this purpose, I employ a gauge and a test bar of metal that can be held at an exactly predetermined distance from the tip of the torch, in fixed relation thereto so that the diver can closely inspect his jet and the effects of his jet on the metal. This makes it practical to supply the submarine torch with adjusting valves to be manipulated by the diver until the desired effect is produced on the test bar. In this work, an adjustable gauge for the test bar is mounted on the tip of the torch so that when the desired adjustment is attained, it is only necessary to displace the test bar and place the gauge of the torch in direct contact with the hull of the ship or other metal to be cut, whereupon precisely the same perfect heating effect will be had on the work that was had on the test bar.

An important development is that this method of testing and adjusting with laboratory exactness under most trying under-water conditions, soon teaches the diver precisely what positions he should set his various valves, after he has once got started on any particular job, other adjustments for substantially changed conditions being effected by resort to the test bar or to another novel method which I have discovered. The latter discovery is that the relation between the gases used, can be easily ascertained at any depth by opening valves one at a time and adjusting each to get the proper length of bubble of each gas. For a proper mixture, the ratio of these lengths is constant at each depth. Preferably, all valves are marked so that the operator can note their individual adjustments and can reset them to the required opening when all gases are turned on together.

None of the proposed under-water torches of the prior art disclose what I have discovered to be the desirable relation for discharge of the primary fuel gas and oxygen mixture with reference to the jet for the cutting oxygen. The same thing is true of the air sheath, with reference to the fuel and oxygen jets. I prefer to have the primary gas-oxygen mixture discharged through a circularly arranged set of parallel, relatively

small jets and the cutting oxygen being discharged through a central parallel jet. The air sheath jet is a thin annulus surrounding and discharging substantially parallel with the jets of the fuel-oxygen mixture and the cutting oxygen jet. With such parallel arrangement of all the gas streams, turbulence is avoided and the air sheath surrounding the flame simulates and reproduces with satisfactory approximation the combustion supporting relation of atmospheric air to the flame, in the operation of an above-water torch of similar construction.

Another feature involves discovery that there are fundamental but more or less obscure difficulties attendant upon use of acetylene and other higher carbon fuel gases, or mixtures, which have been supposed to be essential for under-water work, because their high calorific values were considered necessary for properly preheating submerged metal. Acetylene gas, for instance, is unstable when used under pressures and may be very dangerous when employed in a torch at any considerable depth. When subjected to depth pressures near and above 15 pounds above atmosphere, it is likely to detonate or decompose explosively, a danger entirely different from and less understood than the ordinary blow back explosions to which ordinary oxygen blow pipe mixtures are liable. Other of the high carbon gases and mixtures are subject to the same and other practical difficulties resulting from the pressures under which they must be supplied to the jet. Freezing up is a common difficulty attendant upon the use of these gases. While various features of my invention are applicable to the use of such fuel gases, particularly at small depth, an important discovery is that substantially pure hydrogen, though it has far less fuel value, is, of all others, the one that can be safely used at the greatest depths. Moreover, when properly used in accordance with my invention, its fuel value and heating effect are entirely sufficient for under-water work. These discoveries reverse the teaching of the present-day art.

The above and other features of my invention will be more evident from the following description in connection with the accompanying drawings, in which

Fig. 1 is a side elevation of a torch and attachments in accordance with my present invention;

Fig. 2 is a view partly in section, showing the various supply pipes and air sheath nozzle in axial section in the plane of the paper, the burner tip being shown in elevation;

Fig. 3 is a section on line 3—3, Fig. 2;

Fig. 4 is a vertical section through the burner tip in the same plane as Fig. 2;

Fig. 5 is a detail view of the test bar and attachment for the torch; and

Fig. 6 is an elevation of the gauge viewed at right angles to the direction shown in Fig. 1.

In these drawings, some of the structural features of the torch may be substantially the same as found in certain makes of above-water torches but never in under-water torches so far as I am aware. As concerns the burner tip and certain other features 10 hereinafter described, their selection for submarine work and particularly for great depth work is because of their peculiar adaptability for use in the new combination and under new conditions contemplated by my 15 present invention.

Among the features that may conform to above-water practices, are the handle 1, through which the hydrogen supply pipe 2 is connected to the hydrogen supply hose 3, 20 through the controlling valve 4; the pipe 5 for the primary oxygen, controlled by valve 6 supplied from oxygen hose 7; and pipe 9 for the cutting oxygen which is also derived from hose 7 but separately controlled by 25 means of valve trigger 10. As will be evident from Figs. 2, 3 and 4, the hydrogen pipe 2 discharges into annular cavity 11, in head 12 and thence through radial holes 13 to the parallel fuel-oxygen nozzles 14, 14. 30 The oxygen from pipe 5 passes into the annular space 15, which is cut off from 11 by contact of collar 16 with the contracted walls within the head 12, and from said annular space 15 the oxygen flows through radial 35 holes 17, into each of the same jet forming passages 14, 14, that are supplied through the hydrogen inlets 13, there being an oxygen inlet 17 and a hydrogen inlet 13 for each of said passages 14.

40 The cutting oxygen from pipe 9 is discharged into cavity 18 in the base of said head 12, and flows thence through the axial passage 19, around which the oxyhydrogen jets 14 are circularly arranged.

45 The improved attachment for affording my novel air sheath in combination with the flame jets 14, 14 and cutting jet 19, includes an exterior jacket or nozzle which may comprise a screw-threaded base portion 20, 50 adapted for clamping engagement with the annulus 21 of the above described oxyhydrogen nozzle. This air sheath nozzle includes a cylindrical jacket portion 22, surrounding and of substantially greater diameter than 55 said jet nozzle, to afford an annular interspace 23 of substantial cross-section, permitting relatively slow non-turbulent flow of the air up to a point 24 near the tip of the nozzle. Here the cross-section of this annular air-passage is greatly reduced, as 60 shown. In this reduced portion, the inner wall 25 of the air sheath nozzle is approximately cylindrical and the tip of the nozzle at 26 is near enough cylindrical so that the 65 air sheath jet is discharged approximately

parallel with the jets from passages 14, 14, which latter are to be protected and supplied with air by said air sheath jet. The air is supplied to annular space 23 through a pipe 27, secured at one end by a gastight union 28, to a nipple 29 screw-threaded in collar 20 as shown, and at the other end by a union 30 secured to a valve 31 supplied through pipe 32 and hose 33. The air sheath supply pipe 27 and its connections 31, 32, 33 are held in fixed relation to the handle 1 of the torch by collars 34, 35 detachably secured about said handle. The jacket thus constructed distributes compressed air or other similar gas in a uniform stream around the tip of the torch in a direction parallel with the flame and oxygen jets and at a sufficient pressure entirely to displace the liquid from the vicinity of the torch tip, and to form a proper cavity of air, free of liquid in which ignition and combustion of the gases to be burned can take place. The chamber diameter is reduced near the end of the tip, so that the air is forced to escape as a film completely surrounding the tip. The length of the jacket is required to be from about $\frac{1}{4}$ inch longer than the tip to $\frac{1}{4}$ inch shorter; a jacket materially longer than this will prevent proper preheating of the metal by cooling it and one materially shorter will allow the film air to escape without properly protecting the flame from the liquid. A long jacket will also cause the compressed air to mingle with and dilute the pure oxygen discharged through the cutting hole in the tip and make cutting impossible. The valve 31 is provided on or in the vicinity of the torch handle so that the operator may adjust the pressure of the air supplied to the jacket so as always to maintain a film of air around the tip properly to protect the flame, regardless of the depth of liquid, friction in hoses, and variations in pressure of the air supply at the surface, provided only that an excess pressure of air be maintained on 100 annular space 23.

105 My novel gauge as shown in Figs. 1 and 6, includes fingers 36 extending parallel with the axis of the burner nozzle, having end gauge surfaces 37, in a plane at right angles to said axis. The gauge fingers are made adjustable axially of the jet, preferably by making them integral with a screw nut 38 engaging threads 39 on exterior of the air sheath nozzle. Such an adjustable gauge or 110 spacer is practically essential in under-water work to keep the tip of the torch at the proper distance from the metal, proper and continuous operation being otherwise impossible. This distance condition is far more 115 critical than would be inferred from atmospheric practice where a moderate deviation in distance is permissible without seriously affecting the speed of cutting. For under-water work the spacer should be accurately 120 125 130

adjusted to suit the condition at the depth at which cutting is to be done.

While this gauge construction and mounting is new and useful for a diver highly experienced in the use of my apparatus in accordance with the above described methods, I prefer to provide, even for the experienced diver, a means for supporting a metal test bar 40 in fixed contact with the gauge surfaces 37 of gauge fingers 36. A convenient and simple form of clamp comprises members 41, 42 formed at their outer ends with opposite edge clamps 43, 44 engaging the test bar 40. At their opposite ends, they 15 are formed for detachable engagement with the torch structure. The portions 46, 47, straddle the pipes 9, 5, 2 and 27, said pipes being preferably all in the same plane so that the plane of the clamp and the bar held 20 thereby is substantially fixed. Preferably, the clamps 41, 42 are of spring material held together as by screws 48 and clamping nuts 49, 49, preferably designed so that the bar 40 will be securely but slidably held in the 25 clamping jaws 43, 44, while the mounting jaws 46, 47 will be securely held to the pipes, for ready attachment or removal. To facilitate the attachment, the outer ends 46a, 47a, are preferably curved outward as shown.

30 From the statement of the nature and objects of my invention, first above given, the uses of the above described apparatus will be obvious. The above-water source of supply through hose pipes 3, 7 and 33 requires 35 no special control provided only the pressure be in excess of the maximum pressure required at any depth at which it is proposed to work. The diver will first turn on and adjust one of the gases as, for instance, the 40 hydrogen, to get a suitable length of cavity in the water and will then note the proper setting of the valve which he then closes. He will then do the same thing separately for the oxygen and for the air, adjusting for the 45 length of bubble of each which he knows by experience will be necessary for the predetermined adjustment of the hydrogen. Then turning on all the valves to the predetermined setting, the mixture may be ignited in 50 any of the usual ways as by an electric sparker inserted in the bubble. The test bar may be applied as shown in Fig. 1 so that in full view and at closest range the diver may further adjust the oxygen and hydrogen 55 by means of valves 4 and 8, until the flame is exactly right and heats a white hot spot on the bar. If desired, he may then test the oxygen cutting jet by manipulation of trigger 10 to cause combustion of the iron or 60 steel. Having thus attained desired operation on the test bar at the desired depth, he will then apply the torch with the gauge surfaces 37 in contact with the metal to be cut, with the certainty that maximum heating 65 and cutting effects will be obtained. The

test bar and method of using the same is not specifically claimed herein, being reserved for another application.

It will be understood that an under-water torch constructed in accordance with my invention will be of great use in many other industrial operations besides salvaging ships and the like. For instance, the torch may be used by a fireman for cutting girders, etc. during a fire, while they and the torch are protected from the fire by floods of water from the fire hose; or, the torch may be used indiscriminately for cutting metal above or under water in a cellar which has been flooded in attempts to put out the fire.

A more conventional commercial use constituting a distinct invention, is the shaping of refractory metal castings as, for instance, chrome steel, by submerging such castings in a suitable liquid and then using my torch for cutting the submerged casting to shape. In this way, the heat may be localized so that the cutting torch can be used to shape the surface, yet the liquid will confine excessive heating and damage of quality to a very thin layer of the metal adjacent the cut surface, leaving the rest of the metal unaffected. For this purpose, hydrogen gas giving a temperature somewhere near 2,500° F. is distinctly preferable to acetylene, which gives temperatures nearly 1,000 degrees higher.

I claim:

1. An under-water cutting torch having a burner nozzle for discharge of an oxygen-fuel gas mixture, a substantially cylindrical sheath terminating in a nozzle for surrounding the same with a sheath of air or the like, in combination with a gauge mounted for adjustment lengthwise of said burner nozzle, said gauge comprising diametrically opposite portions of equal length projecting endwise beyond the nozzle and endwise adjustable by a screw-threaded mounting on said nozzle.

2. An under-water-cutting torch having a burner nozzle for discharge of an oxygen-fuel gas mixture, a nozzle for surrounding the same with a sheath of air or the like, the passages for discharge of the oxygen, the fuel gas, and the air, being approximately parallel in combination with a gauge mounted for adjustment lengthwise of said burner nozzle, said gauge comprising diametrically opposite portions projecting endwise beyond the nozzle and having a screw-threaded mounting thereon, and means for independently supplying and adjustably controlling oxygen, fuel gas and air to cool the torch nozzle.

3. The method of adjusting an oxygen-fuel gas flame surrounded by an air sheath, for under-water cutting, which method includes adjusting the proportions of the gases by separately and successively projecting and adjusting the pressures of unignited jets

of each, at substantially the depth at which the cutting is to be performed to obtain a desired ratio of lengths for the respective bubble cavities formed by each gas separately, then simultaneously supplying all of the gases to their jets at the respective pressures thus predetermined.

4. The method of under-water cutting of metal, which includes producing and maintaining a flame of minimum turbulence by supplying the mixture of gaseous fuel and oxygen to the flame through a plurality of parallel circularly arranged jets, protecting said jets and the flame by a surrounding air jet discharged approximately parallel with said jets; and adjusting the proportions of the gases by separately and successively projecting and adjusting the pressures of unignited jets of each, at substantially the depth at which the cutting is to be performed to obtain a desired ratio of lengths for the respective bubble cavities formed by each gas separately, then simultaneously supplying all of the gases to their jets at the respective pressures thus predetermined.

Signed at Westfield, in the county of Union, and State of New Jersey, this 15th day of November A. D. 1927.

EDWARD ELLSBERG.
